UNITED STATES PATENT OFFICE

ERNEST HUFF, OF MILWAUKEE, WISCONSIN, ASSIGNOR TO AMERICAN LACE PAPER COMPANY, OF MILWAUKEE, WISCONSIN, A CORPORATION OF WISCONSIN

CONTAINER

Application filed October 31, 1928. Serial No. 316,293.

This invention relates to improvements in containers.

It is the primary object of this invention to provide an improved rim construction for 5 a pleated container made of paper or other thin sheet material with a view to reinforcing the margin of the container more adequately against distortion than has been possible in constructions heretofore known, 10 while also providing a rim which will facilitate drinking and pouring from the container, will be self-supporting without the use of paraffin, will hold in their predetermined relation the several pleats of the cup and will 15 make possible the packaging of a large number of containers in nested relation within a relatively very small space.

It is a further object of the invention to provide a bead construction such that the 20 size and shape of the bead may be proportioned to the size and shape of the container.

In the drawings—

Figure 1 is a view in perspective of a paper container embodying this invention broken 25 away to a radial section to expose the rim and base construction thereof.

Figure 2 is an enlarged fragmentary detail section of one form of rim embodying this invention.

30 Figure 3 is a fragmentary detail section of the base of the cup shown in Figure 1.

Figure 4 is a fragmentary view in section of a container embodying this invention and having a slightly modified form of rim.

35 Like parts are identified by similar reference characters throughout the several views.

The container to which this invention relates is preferably made from a single sheet 40 of paper by a well-known pleating operation whereby the sides 5 of the cup are formed upwardly from the base portion 6 thereof, the sides being provided with pleats as shown at 7 having progressively increasing degrees 45 of overlap toward the top of the cup to take up the excess of material in the single sheet from which the cup is formed.

In accordance with this invention the un- 50 pleated bottom portion 6 of the container is preferably embossed upwardly at its center

in the manner shown at 8. This has an unusual advantage in a paper article because paper is so thin and so highly flexible as to make it peculiarly subject to distortion under load and the bottom of a paper container 55 is usually bowed downwardly under pressure of the contents of the container with the result that the container does not stand upright when placed upon a table or like support. It is found that the upwardly embossed center 8 of the bottom portion 6 of the container not only tends to reinforce the bottom but also lifts the central portion thereof sufficiently to compensate for any slight downward convexity which may result from the introduction of material into 60 the container. The container therefore will stand erect and will normally contact with a table only upon the annular unembossed portion of its base 6 which is immediately adjacent the periphery thereof.

The treatment of the upper marginal portion of the cup is most important. As previously indicated, it is not desired to use paraffin or adhesive between the pleats or folds 75 to hold the overlapping portions together. It becomes necessary therefore to rely upon the margin of the cup to perform this function while at the same time achieving the other objectives noted in the foregoing statement of the objects of this invention. Accordingly, the material is carried outwardly at 9, thence downwardly at a sharp angle at 10 in spaced relation to all other parts of the container, thence upwardly at 11 in contact 80 with the outer and upper surface of the side portion 5 of the container, and thence outwardly at 12 immediately beneath the marginal outward extension 9 above described and in contact with the under surface thereof. 85

It will be noted that the construction above described comprises a marginal bead for the cup which is substantially of triangular cross-section, all lines thereof being straight in cross-section. The completed margin may 90 if desired be strengthened by a crimping operation involving the application of pressure at 15 which slightly deforms the triangular cross-section of the bead with the result that the bottom fold between portions 100

10 and 11 thereof is tightly creased and tends to hold its shape more adequately than would otherwise be the case. It is found that the triangular cross-section of the marginal bead formed in accordance with this invention is well adapted to satisfy the objects of the invention as hereinbefore specified. It not only holds the pleats together, as would a bead of any other shape, but in addition a 10 bead having a general triangular cross-section has proven exceptionally resistant to distortion of the cup or container both in horizontal and vertical directions.

The fact that the elements 9, 10, 11 and 12 of the bead are rectilinear in cross-section 15 gives them much more strength to resist pressure than would be the case if they were curvilinear, since a curved sheet of paper will readily bow and will yield by increasing 20 its convexity under pressure. The stiffness of a marginal bead made in accordance with this invention is particularly apparent under downward pressure, the portion 10 of the bead serving as a brace to support the more 25 or less flat upper surface 9 thereof from the side wall 5 of the container which is reinforced by the portions 11 and 12 of the bead. The whole structure forms a truss-like assembly which highly resists distortion.

30 It is broadly immaterial to the present invention whether the upper surface of the bead is perfectly flat in a horizontal plane, as shown in Figure 2, or occupies a position inclined from the horizontal. In Figure 4 I have shown this upper element 9 of the bead 35 to be upwardly inclined. This construction results in flattening to a considerable degree the triangular form of the bead as compared with the form illustrated in Figure 2 which will be noted to be almost a right angle triangle. Due to the fact that the angle of the 40 bead with the side of the cup is more obtuse in Figure 4 than in Figure 2 it will be found that the Figure 4 construction will not be quite as rigid as that shown in Figure 2 although some of the other advantages of the 45 triangular bead will be somewhat enhanced.

The triangular form of bead is peculiarly well adapted for use in containers from which 50 liquids are to be drunk or poured. The contour of the triangular bead is not only better fitted to the lips than the margin of any other paper container with which I am familiar but it is also adapted to pour liquids without 55 encouraging the dripping of some of the liquid down the sides of the container. In these particulars the more acute angle at the outer peripheral margin of the Figure 4 bead 60 may be found preferable to the less acute angle of the periphery of the bead shown in Figure 2.

In the matter of nesting the containers within limited space it is also desirable to reduce the depth of the triangular cross-section 65 of the bead as far as is consistent with the de-

sired strength thereof. Regardless of the particular contour of the triangular bead it will be found possible to nest a greater number of cups with such beads in a given space than could occupy such space if the beads were otherwise formed. With the Figure 4 construction, however, the number of cups which may be so nested will exceed the number of cups of the Figure 2 construction which may be packaged in like space. It will 70 be apparent therefore that the particular shape of the triangular bead may be varied as desired in accordance with the attributes most sought for the particular container to be made.

75 It is also possible to use adhesive material between the several component parts of the triangular bead herein disclosed and it will be found that under such circumstances the rigidity of the completed cup will be even greater than it is possible to achieve through the mere folding of the bead and crimping it to triangular form without adhesive.

80 It is found that the triangular bead herein disclosed is not only comparatively rigidly 90 resistant to forces tending to press downwardly upon the bead or margin of the cup but that it also resists lateral pressure tending to distort or collapse the cup. It is found that in this particular bead herein disclosed 95 produces results which are particularly noticeable in the triangular form but are not necessarily restricted to that form.

100 It will be obvious that a bead of which the upper surface or marginal flange is substantially rectilinear in cross section and is braced in any way from an intermediate portion of the cup wall will have greater strength than a bead which is not thus rectilinear in cross section at its top surface or is not so braced. In fact the bracing is of exceptional importance where the bead or marginal flange portion of the cup is rectilinear in cross section 105 since any displacement of the flange will tend to make distortion of the cup possible, whereas if the flange is held substantially in its original position its rectilinear shape will resist distortion of the rim of the cup to a degree which is remarkable in an article of paper.

110 115 I claim:

1. A new article of manufacture comprising a paper container substantially circular in plan providing integrally a bottom and an annular side wall, the marginal peripheral portion of the side wall being extended outwardly, thence back to said wall at a point spaced from the top thereof, and thence along said side wall in contact therewith whereby to provide a bead of generally triangular cross-section integral with the top margin of said wall and braced from an intermediate portion thereof, the bend between the outwardly extended and return portions of said bead being relatively sharp whereby to facili- 120 125 130

- tate drinking and pouring from said container.
2. The combination with a paper receptacle comprising integrally a round bottom and an annular pleated wall, of a peripheral reinforcing bead integral with the upper margin of said wall and comprising a first portion extending upwardly from said wall at an obtuse angle therewith, a second portion bent back at an acute angle and extending rectilinearly toward a part of said wall spaced from the top thereof, and a third portion extending upwardly at an acute angle from said second portion along said wall, said last mentioned angle being sharply creased, and a fourth portion immediately beneath said first portion whereby to provide a generally triangular contour in cross-section with an outwardly exposed apex formed to facilitate
- 10 drinking and pouring and braced with comparative rigidity from said wall notwithstanding the formation of said wall and bead from light material such as paper or the like.
3. A substantially circular paper cup having a rim substantially triangular in cross section formed by an outwardly directed flange having an extension bent in a downward and inward direction to form an apron wall for the rim extending to and engaging
- 25 the cup wall and spaced from said flange.
4. A substantially circular paper cup made from a single blank having a bottom, pleated side with overlaps, and a rim substantially triangular in cross section formed by an outwardly directed flange having an extension bent in a downward and inward direction to form an apron wall for the rim extending to and engaging the cup wall and spaced from said flange.
- 30 5. A substantially circular paper cup having a rim substantially triangular in cross section formed by an outwardly directed substantially rectilinear flange having an extension bent in a downward and inward direction to form an apron wall for the rim extending rectilinearly to and engaging the cup wall and spaced from said flange.
6. A substantially circular paper cup having a rim substantially triangular in cross
- 35 50 section formed by an outwardly directed flange having an extension bent in a downward and inward direction to form an apron wall for the rim extending to and engaging the cup wall and spaced from said flange, said
- 55 apron wall joining an upwardly directed portion bent therefrom and having one surface engaging the cup side below said flange.
7. A substantially circular paper cup having a rim substantially triangular in cross
- 30 60 section formed by an outwardly directed flange having an extension bent in a downward and inward direction to form an apron wall for the rim extending to and engaging the cup wall and spaced from said flange, said
- 65 apron wall joining an upwardly directed
- portion bent therefrom and having one surface engaging the cup side below said flange,
- the said flange, apron wall, and last-mentioned wall being substantially rectilinear.
8. A substantially circular paper cup having a rim substantially triangular in cross section formed by an outwardly directed flange having an extension bent in a downward and inward direction to form an apron wall for the rim extending to and engaging
- 70 75 the cup wall and spaced from said flange, said apron wall joining at a sharp crease an upwardly directed portion bent therefrom and having one surface engaging the cup side below said flange.
9. A substantially circular paper cup having a rim substantially triangular in cross section formed by an outwardly directed flange having an extension bent in a downward and inward direction to form an apron wall for the rim extending to and engaging
- 80 85 the cup wall and spaced from said flange, said apron wall joining an upwardly directed portion bent therefrom and having one surface engaging the cup side below said flange, said last-mentioned wall extending upwardly along the cup side toward said flange and joining a wall bent outwardly therefrom beneath and in engagement with the undersurface of said flange.
10. A paper cup having side walls downwardly convergent along substantially straight lines and a rim substantially triangular in cross section formed by an outwardly directed substantially rectilinear flange having an extension bent in a downward and inward direction to form an apron wall for the rim extending rectilinearly to and engaging the cup side walls and spaced from
- 90 95 said flange.
